UNITED STATES PATENT OFFICE.

CHARLES P. STEINMETZ, OF SCHENECTADY, NEW YORK, ASSIGNOR TO THE GENERAL ELECTRIC COMPANY, OF NEW YORK.

INDUCTOR-DYNAMO.

SPECIFICATION forming part of Letters Patent No. 594,145, dated November 23, 1897.

Application filed August 12, 1897. Serial No. 647,963. (No model.)

To all whom it may concern:

Be it known that I, CHARLES P. STEINMETZ, a citizen of the United States, residing at Schenectady, in the county of Schenectady, State of New York, have invented certain new and useful Improvements in Inductor-DYNAMOS, (Case No. 589,) of which the following is a specification.

My invention relates to alternating-current dynamos of the inductor type, and has for its object to remedy some of the difficulties which have been met with in designing satisfactory machines of this class. In inductor-dynamos the armature and field-magnet coils are stationary and the induction is produced by a change in the path of the magnetic flux effected by the teeth or poles of the rotating inductor. In consequence in part of the magnetic circuit the magnetism varies, and this part, to avoid eddy-currents, must be laminated, while in the other parts the magnetism is stationary and solid material may be used. It is therefore of importance to avoid changes in magnetism in the solid part of the structure in order to avoid excessive heating and loss from eddy-currents.

During the rotation of the inductor the length of the path of the lines of magnetic force, and thereby the reluctance, varies periodically in the laminated portion of the armature, which tends to make the magnetic density vary periodically also. To keep this periodic variation of magnetic density from extending into the solid part of the magnetic circuit, I insert an auxiliary air-gap between the solid and the laminated part of sufficient length to make the magnetic reluctance of the shortest and of the longest path across the armature-iron and auxiliary air-gap practically equal, and thus the magnetic density at the point of entrance into the solid part of the magnetic circuit practically uniform.

Another feature of my invention consists in the use, in an inductor-dynamo, of a short-circuited or squirrel-cage winding surrounding the outer edge of the armature-iron. The magnetic reluctance of the air-gap between the inductor and the armature, especially in unitoothed single-phase machines, is less when the inductor-tooth stands in front of an armature-tooth than when it stands in front

of a slot. Thus the magnetism in the latter case tends to decrease, and this induces eddy-currents in the whole magnetic structure. The use of the short-circuited winding, for 55 reasons more fully to be pointed out, tends to obviate this difficulty.

The accompanying drawings show a machine constructed according to my invention, it being applied to a dynamo of the well-known 60 Thomson inductor alternator type; but it might equally well be applied to any other machine of the same general class.

Figure 1 is an end elevation, partly in section, of such a machine; and Fig. 2 is a side 65 elevation, partly broken away for convenience of illustration.

In Fig. 1, A is the yoke or external portion of the armature-core. B is the inductor, consisting of the usual yoke F and the laminated 70 teeth b b. C C are the armature-teeth, consisting, as is usual in such machines, of laminated iron, the yoke E being ordinarily made of cast-iron or mild steel. Surrounding the inductor and supported by the yoke are the 75 field-magnet coils E' E', they being, as is well understood, stationary. In the machine illustrated each of the armature-teeth is surrounded with a single coil D, but this is merely typical of any selected type or connection of winding. G is the auxiliary air-gap to which I have referred in my statement 80 of invention, separating the laminated armature-iron from the yoke E. Between the yoke F of the inductor and the supporting-yoke E 85 of the armature is the air-gap K, and the usual air-gap e is also located between the inductor and the armature. The action of this part of my invention will be best understood from Fig. 2. The magnetic lines entering from the tooth b in the upper part of the figure and threading the coil spread out in both directions in the iron of the armature, reaching the yoke E at the point s in a practically straight line from the tooth and at the point t over the path y, which is curved 90 and is considerably longer than the path x, having, therefore, higher magnetic reluctance. The magnetic density at s will be greater than at t. By the rotation of the inductor at the next moment the inductor-tooth b will stand in front of the next tooth of the

armature, and the path to the point *t* will be approximately straight, while that to the point *s* will be curved, and thus higher density will exist at the point *t* than at the point 5 *s*. To avoid these pulsations of magnetism in the yoke *E* is the object of the air-gap *G*. The reluctance of this gap being very large 10 as compared with the reluctance of the armature-iron (as pointed out in the statement 15 of invention) makes the total reluctance of the path *y* practically equal to the reluctance of the path *x*, and thereby insures practically a uniform distribution of magnetism in the yoke.

15 To assist the effect to which I have referred, I also provide a short-circuited squirrel-cage winding consisting of the copper pins *I*, Figs. 1 and 2, which pass through the iron of the armature near its outer edge and are connected upon each side of the iron by the short-circuiting bands *II*, also of low-resistance metal. Any pulsation or variation of the magnetic flux reaching the outside of the armature acts to induce secondary currents in 25 this short-circuited winding. These currents tend to magnetize at the points of lower magnetic density and to demagnetize at the points of higher density, and thus cause a uniform distribution of the magnetic flux at the outer 30 part of the armature—that is, when the flux enters the solid structure. The action of this winding is also beneficial in causing uniform distribution of magnetism and in preventing pulsation of the magnetism in the entire magnetic circuit due to the differences of reluctance in the main air-gap of the machine 35 caused by the revolution of the inductor. As already pointed out, the reluctance is less when the inductor-teeth stand in front of the 40 armature-teeth and greater when they stand in front of a slot, thus giving rise to changes in the distribution of the flux and inducing eddy-currents in the whole structure. It has

been proposed to remedy this to some extent by winding the field-magnet coils *E'* upon a 45 solid copper ring or spool. While this is useful, the construction which I have indicated acts in a more efficient manner because it influences directly the armature-iron of the machine. 50

What I claim as new, and desire to secure by Letters Patent of the United States, is—

1. An inductor-dynamo, comprising a revolving inductor and a stationary armature, the latter having portions of laminated iron 55 and a solid yoke, with an auxiliary or additional air-gap in the armature-iron.

2. An inductor-dynamo having a revolving inductor and stationary armature, the armature having on its outer edge a short-circuited 60 or squirrel-cage winding.

3. An inductor-dynamo, comprising a revolving inductor and a stationary armature, the armature provided with an auxiliary air-gap in its circuit and a short-circuited or 65 squirrel-cage winding near its outer edge.

4. In a dynamo, an auxiliary or additional air-gap between the laminated and the solid parts of the magnetic circuit.

5. In an inductor-dynamo, an air-gap between the laminated and solid parts of the 70 armature-iron.

6. In a dynamo-electric machine of the inductor type, the combination of a polar inductor, and an annular magnetic structure 75 recessed to receive the armature-coils and having its magnetic reluctance increased by an air gap or gaps, of high reluctance compared with the reluctance of the armature-iron. 80

In witness whereof I have hereunto set my hand this 10th day of August, 1897.

CHARLES P. STEINMETZ.
